INVENTOR.
HOWARD W. PARTLOW

BY

Thomas L. Wilder

ATTORNEY.

UNITED STATES PATENT OFFICE.

HOWARD W. PARTLOW, OF UTICA, NEW YORK.

SLUG GUIDE.

1,411,457.

Specification of Letters Patent.

Patented Apr. 4, 1922.

Application filed March 1, 1919. Serial No. 230,163.

To all whom it may concern:

Be it known that I, HOWARD W. PARTLOW, a citizen of the United States, residing at Utica, in the county of Oneida and State of New York, have invented certain new and useful Improvements in Slug Guides, of which the following is a specification, reference being had therein to the accompanying drawing.

10 My invention relates to a slug guide for typesetting machines, and I declare the following to be a full, complete and exact description thereof sufficient to enable anyone skilled in the art to which it appertains to 15 make and use the same, reference being had to the accompanying drawings in which like reference characters refer to like parts throughout the specification.

The object of the invention is to provide 20 a device that will prevent the upper end of a slug, as it moves down the chute of the typesetting machine onto the galley thereof from tipping forward and thereby transposing when it reaches the galley. The device

25 is made adjustable, whereby it can be used to accommodate slugs of different lengths. It also has a yielding member for the escape of the slugs should they become clogged in the machine.

30 The object will appear by referring to the drawings in which:

Fig. 1 is a perspective view of the salient parts of a typesetting machine showing 35 slug adjusting device attached thereto;

Fig. 2 is a detail enlarged view of the slug 40 adjusting device, showing the same in perspective;

Fig. 3 is a detail enlarged view, showing 45 a central vertical section of the device, parts being illustrated also in elevation;

Fig. 4 is an enlarged detail view of an 50 arm and immediate parts employed on the device;

Fig. 5 is an enlarged detail view of a 55 spring used;

Fig. 6 is an enlarged detail perspective view of a hollow arm employed;

Fig. 7 is an enlarged detail perspective 50 view of a stud employed to hold the hollow arm of Fig. 6;

Fig. 8 is a fragmentary perspective view 55 of parts of the typesetting machine, showing a bracket to which the slug adjusting device is attached.

Referring more particularly to the drawings, the bracket of a typesetting machine

in which is located a chamber for the passage of the slugs —1— from the typesetting machine to the galley 3 is represented by 2. The galley is equipped with a yielding arm 60 4. The slugs 1 are pushed sidewise along the galley 3 by a vibratory lever 5. The above parts of the machine are old and well known in the art.

In this instance, however, which we claim 65 as new, the bracket 2 has a lateral face 6 with a threaded aperture 7 for the attachment of a like bracket 8 holding or carrying the novel slug adjuster which is the object of my invention. The slug adjuster is represented by 10 and comprises a piece of metal or member 11^a having a long narrow slot 11 in which slides a stud 12. The stud 12 is reduced at 13 to fit the slot 11 and has attached by a screw 14 to its outer end a 75 spring 15, whereby the stud 12 may be held at any given location along the member 11^a. The spring 15 has upturned flanges 24—24 to guide it along the slot 11 of the member 11^a.

The opposite or free end of the stud 12 is reduced at 16 to provide a bearing for the mounting of the hollow arm 17 which is recessed at 18. The hollow arm 17 is fulcrumed to the stud 12 by a pin 19. It is 85 covered with a rubber sleeve 23. The ends of the hollow arm 17 are squared at 21 and rounded off at 22, whereby to permit the hollow arm 17 to turn upon its fulcrum 19 in one direction only.

The hollow arm 17 is held normally in 90 perpendicular relation to the member 11^a and in alignment with the stud 12 or as illustrated in Figs. 1, 2 and 3 by a spring 25 that is attached at one end to an aperture formed 95 in the stud 12 at 26 and at the other end to a pin 27 mounted to the arm 17. This construction permits the arm 17 to yield, whereby to release the slugs 1 and allow them to fall out of the chamber in the bracket 2, 100 should said chamber become clogged therewith.

The operation of the device is very simple. The yielding hollow arm 17 is set in accordance with the length of slug —1— 105 that is being used in the typesetting machine by pushing the arm 17 up or down along the slot 11 of the member 11^a. The exact location of the arm 17, whereby it will be in position to touch the upper end of the slug 110 —1—, as the same is ejected into the chamber of the bracket 2, may be determined by

the graduation marks or numerals disposed along the member 11^a adjacent the slot 11.

The bracket 8 is spaced from the member 11^a by bars 30—30, whereby the spring 15 is able to move freely therewith.

As the slugs —1— are pushed into the chamber of the bracket 2 by the ejector 31, the same will be prevented from tipping forward by the arm 17. At the same time

10 the arm 17 will offer no resistance to the descent of the slug 1—1 in proper position toward the galley 3, where it will be pushed gradually in a lateral manner by the vibratory lever 5.

15 Having thus described my invention what I claim as new and desire to secure by Letters Patent is:

1. In a slug guide for typesetting machines, an arm, spring means for holding 20 said arm in adjusted vertical position, whereby to locate it with reference to the length of a slug adapted to pass thereby, a pivot for mounting said arm, and spring means for permitting said arm to yield to 25 release said slugs should they become clogged in the typesetting machine.

2. In a slug guide for typesetting machines, an arm pivotally mounted, a flat spring for holding said arm in adjusted 30 vertical position, whereby to locate the same with reference to the length of slug, and a spring for permitting said arm to turn on its pivot to release said slugs should they become clogged in the typesetting machine.

35 3. In a slug guide for typesetting machines, a pivotally mounted yielding arm, a metal plate having a narrow slot, a spring for holding said arm at any location along said slot, whereby it will prevent the slugs, 40 as they come from the machine from tipping forward, and a second spring for allowing said arm to turn on its pivot in a yielding manner.

4. In a slug guide for typesetting ma-

chines, a member having a slot, a pivotally mounted yielding arm adapted to slide along said slot, whereby it will be in position to prevent the slugs from tipping forward, as they come from the typesetting machine, a flat spring for holding said arm 50 at any given location along said slot, and a second spring for allowing said arm to turn in a yielding manner upon its pivot.

5. In a slug guide for typesetting machines, a member having a slot, a stud 55 adapted to slide along said slot, an arm pivoted to said stud and adapted to prevent the slugs from tipping forward, as they come from the typesetting machine, a spring for holding said stud at any given 60 location along said slot, and a second spring for allowing said stud to turn in a yielding manner upon its pivot.

6. In a slug guide for typesetting machines, a graduated member having a slot, 65 a pivotally mounted arm adapted to slide along said slot, whereby it will be in position to prevent the slugs from tipping forward, as they come from the typesetting machine, a spring for holding said arm at 70 any given location along said slot, and a second spring for allowing said arm to turn in a yielding manner.

7. In a slug guide for typesetting machines, a member attached to a typesetting 75 machine and having a slot, a stud slidably mounted in said slot, an arm fulcrumed to said stud, a spring for holding said arm in alignment with said stud, a second spring having upturned flanges, whereby to hold 80 said stud and arm at any given position along said slot, whereby to prevent the slugs from tipping forward, and means for allowing said arm to turn in one direction only on its pivot.

85 In testimony whereof I have affixed my signature.

HOWARD W. PARTLOW.
